UNITED STATES PATENT OFFICE.

EUGENE WINTON SUSNICH, OF WELLSVILLE, OHIO, ASSIGNOR TO CHARLES E. WEBSTER, OF WELLSVILLE, OHIO.

AUTOMATIC HEATING SYSTEM.

1,380,687.

Specification of Letters Patent. Patented June 7, 1921.

Application filed February 25, 1920. Serial No. 361,232.

To all whom it may concern:

Be it known that I, EUGENE WINTON SUSNICH, a citizen of the United States, residing at Wellsville, in the county of Columbiana 5 and State of Ohio, have invented certain new and useful Improvements in Automatic Heating Systems, of which the following is a specification.

This invention relates to heating devices, 10 and more particularly to means for heating the water for the cooling system of an automobile internal combustion engine.

One of the main objects of the invention is to provide simple and efficient means 15 which may be readily applied to the cooling system of an automobile engine of the internal combustion type so as to prevent freezing of the same during cold weather. A further object is to provide simple and 20 efficient means for automatically throwing the heating device into and out of operation in accordance with variations in temperature of the water in the cooling system. Another object is to provide means whereby the heating 25 device may be readily connected to a storage battery or to the magneto or other source of electrical energy; as conditions may require. Further objects will appear from the detailed description.

30 In the drawings:—

Figure 1 is a diagrammatic view of a heating device constructed in accordance with my invention, as applied.

Fig. 2 is a fragmentary section through 35 the heater.

A suitably constructed casing 1 is mounted adjacent to one side of the engine A of the automobile, and in rear of the radiator B, this casing is divided by horizontal plates 40 or partitions 2 and 3 into upper and lower water chambers which are connected by a plurality of spaced vertically disposed and narrow water tubes 4. Heating coils 5 are mounted between these tubes and the lower 45 ends of these coils are connected by a wire 6 to one pole of an induction coil 7. The upper ends of the heating coils are connected by a lead 8 to a contact 9 of a thermostat 10 of suitable type mounted in a cap 11 connected by a nipple 12 to the lower water chamber of casing 1. The thermostat includes a slideable rod 13 provided at its upper end with a bridge piece 14 for connecting contact 9 to contact 15 of the thermo- 50 stat when the rod is lowered. As will be

understood, when the temperature of the water in the lower compartment of the casing falls below a predetermined point, rod 13 is lowered so as to connect the contacts 9 and 15 through the medium of bridge 60 piece 14.

Contact 15 is connected by a wire 16, in which is interposed a switch 17, to the other pole of the secondary coil for induction coil 7. One pole of the primary coil of induction coil 7 is connected by a wire 18 to a contact jaw 19, the other pole of the primary coil being connected by a wire 20 to a contact jaw 21. The jaws 19 and 21 coöperate with a two bladed double throw switch 22, 65 one pole 23 of which is connected by a wire 24, in which is interposed a switch 24^a, to wire 6, the other pole 25 of this switch being connected by a wire 26 to wire 16. Switch 22 also coöperates with two contact jaws 27 70 connected by wires 28 to a plug 29 by means of which these wires may be connected to a suitable socket which is connected to an electric light circuit or any other suitable source of electrical energy. The blades of 75 switch 22 fit into contact jaws 30 and 31 positioned a short distance from contacts 21 and 19, when the switch is in the position illustrated. Contact jaw 31 is connected by a wire 32 to one pole of a storage battery 80 33 which may be mounted in any suitable position upon the automobile, and the other pole of this battery is connected by a wire 34 to contact jaw 30.

The upper water compartment of the radiator B is connected by a hose section 90 C to the water jacket of the engine in the known manner, and the lower compartment of the radiator is connected by hose section D to the lower water compartment of casing 95 1 the upper water compartment of which is connected by hose section 35 to the water jacket of the engine.

As will be understood, the water of the engine cooling system circulates through the 100 tubes 4 of the heating device, and through the radiator and the water jacket in the known manner. When this water falls below a predetermined temperature, the thermostat 10 connects contacts 9 and 15. With 105 the switches 17, 22, and 24^a in the relative positions illustrated, current from battery 33 flows through the primary coil of induction coil 7. The induced current in the secondary winding of the induction coil will 110

flow through heating coils 5 so as to heat the water flowing through tubes 4 sufficiently to effectually prevent it from freezing. The storage battery is preferably used when 5 the automobile is standing still on the road. During travel of the automobile, and after the engine has warmed up sufficiently, the switch 22 is thrown into open position, thus saving the battery current. During the time 10 when the automobile is stored away, the heating current may be obtained more cheaply from a local light circuit. To this end, switch 22 is thrown into its other position, switch 17 being opened and switch 15 24^a closed. With the switches in this position, current will flow from plug 29 through wires 28 to wires 24 and 26, and thence through the heating coil, when the thermostat rod 13 is lowered, the storage battery 20 33 and induction coil 7 being cut out. Whenever required by the voltage of the local light circuit, suitable means may be inserted in line 28 to reduce the voltage in the heating coils 5, as indicated by resistance 25 28^a. Preferably, though not necessarily, in practice suitable connections are provided between switch 22 and switches 17 and 24^a, by means of which switch 17 will be closed and switch 24^a opened when switch 22 is 30 thrown into the position illustrated, switch 17 being opened and switch 24^a closed when

switch 22 is thrown into its other operative position. As will be understood, and as indicated herein, slight changes may be made in details of construction and arrangement 35 of various parts of the invention without departing from the field and scope of the same, and I intend to include all such variations, as fall within the scope of the appended 40 claims, in this application in which a preferred form only of my invention is disclosed.

What I claim is:—

In combination with an internal combustion engine including a water jacket, a radiator having its upper water compartment connected to said jacket, a casing having an upper water compartment and a lower water compartment communicating with the water jacket and the lower water compartment 50 of the radiator respectively, tubes connecting the upper and lower compartments of said casing, heating coils mounted between said tubes, a source of supply of electrical energy connected to said coils, and means interposed to the circuit of said source of supply of electrical energy for closing said circuit when the temperature of the water flowing through said casing falls below a predetermined degree. 60

In testimony whereof I affix my signature.

EUGENE WINTON SUSNICH.
